CRUSHER

Edward Kraemer, Plain, Wis.

Application March 25, 1935, Serial No. 12,807

2 Claims. (Cl. 83—53)

This invention appertains to crushers of the type particularly adapted for crushing rock and other solid substances.

One of the primary objects of my invention 5 is the provision of a crusher embodying stationary jaws at the opposite ends thereof, and swinging jaws arranged in facing relation to the stationary jaws, with power means for alternately moving the swinging jaws toward and away from the stationary jaws so as to effectively bring about the crushing of material at each end of the machine.

Another object of my invention is the provision of a double unit crusher so constructed 15 as to crush large pieces of rock at one end thereof, and small pieces of rock at the other end thereof, whereby rocks of a larger size than desired falling from the first crushing means can be conveyed to the opposite end of the machine 20 and recrushed to the desired smaller size.

Another important object of my invention is the provision of novel means for operating the moving jaws of the double unit crusher from a single power-driven cam shaft, in such a manner 25 that when one jaw is being moved to a crushing position, the other jaw is being withdrawn from its operative position so that the shaft will not be subjected to undue stress, and whereby the shaft is under a constant uniform load.

A further object of my invention is the provision of novel means for supporting the moving jaws, and novel means for operating the moving jaws, whereby not only will great crushing power be exerted by said jaws, but whereby 35 said jaws will be given a compound movement toward and away from the stationary jaws, and longitudinally of said stationary jaws, so that the rock will be effectively crushed.

A further salient object of my invention is the provision of a double unit rock crusher including a frame rotatably supporting a cam shaft having a main power jaw rockably mounted on the cam portion of the shaft, and power beams or links rockably mounted on the cam portion 45 of the shaft, the beams being rockably supported intermediate their ends on a swinging Samson post or link, and a supplemental crushing jaw rockably supported by the beams, whereby to bring about the alternate moving of the jaws to a crushing position.

A still further object of my invention is to provide a double unit crusher of the above character, which will be durable and efficient in use, one that will be simple and easy to manufacture,

and one which can be placed upon the market at a reasonable cost.

With these and other objects in view, the invention consists in the novel construction, arrangement, and formation of parts, as will be 5 hereinafter more specifically described, claimed, and illustrated in the accompanying drawings, in which drawings:

Figure 1 is a top plan view of the improved rock crusher, showing parts thereof broken away 10 and in section.

Figure 2 is a longitudinal section through the improved crusher, taken substantially on the line 2—2 of Figure 1, looking in the direction of the arrows.

Referring to the drawings in detail, wherein 15 similar reference characters designate corresponding parts throughout the several views, the letter A generally indicates the improved crusher, which comprises a suitable supporting frame 5. 20 This frame 5 may include longitudinally extending spaced, parallel frame plates 6, which form the side walls of the machine. These side frame plates are held in their proper spaced position by transversely extending tie rods or bolts 7, on 25 which are placed spacing sleeves 8, the ends of which engage the frame plates.

A stationary crushing jaw 9 is arranged at one end of the machine, and this jaw is secured in place in any desired manner, such as by the 30 use of angle bars 10. The angle bars 10 are bolted respectively to the frame plate 6 and the jaw 9. As shown, the jaw 9 extends downwardly and inwardly at an angle, for a purpose which will be later set forth. Arranged at the opposite 35 end of the machine is a transversely extending supplemental stationary crushing jaw 11. This jaw 11 can also be secured to the side plates by means of angle bars 12. As clearly shown in Figure 2, the jaw 11 also extends downwardly 40 and inwardly at an angle.

Rotatably mounted in suitable anti-frictional bearings carried by the side plates 6 is the main cam shaft 13. The ends of the shaft extend beyond the frame plates, and have keyed or otherwise secured thereto relatively large flywheels 14, one of which may constitute a pulley wheel, whereby the shaft can be driven from a prime mover, or the shaft can be driven in any other preferred manner from a desired power plant. 50 Arranged in facing relation to the main stationary jaw 9 is the main swinging crusher jaw 15. This jaw 15 has formed on its upper end the transversely extending bearing sleeve 16, which receives the cam portion 17 of the cam shaft 13. 55

Arranged on each side of the jaw sleeve 16 are parallel links 18, which form in effect a walking beam. The links 18 rotatably receive the cam portions 17 of the shaft, and thus the links are operated in unison with the main crushing jaw 15. The ends of the links 18 remote from the cam shaft 17 receive and support a transversely extending shaft bearing 19, on which is rockably mounted the sleeve 20 of the supplemental swinging crushing jaw 21. The swinging jaw 21 is arranged in facing relation with the supplemental stationary jaw 11.

At a point intermediate their ends the links 18 support the transversely extending shaft 22, and this shaft is rockably supported by the upper end of the swinging Samson post or supporting link 23. It is to be noted that the shaft 22 is nearer the shaft 19 than the cam shaft 13. The lower end of the swinging Samson post or link 23 is rockably mounted on a transversely extending supporting shaft 24, the ends of which are firmly anchored to the frame plates 6.

Novel means is provided for rockably supporting the lower ends of the swinging jaws 15 and 21, and thus I provide a swinging toggle plate 25 for the jaw 15, and a swinging toggle plate 26 for the jaw 21. The inner ends of the toggle plates 25 and 26 are rockably mounted on cross rods 27 and 28 rigidly secured to the side plates 6. The outer ends of the toggle plates are received within sockets 29 and 30 carried respectively by the rear faces of the jaws 15 and 21. The toggle plates 25 and 26 extend downwardly and outwardly toward the jaws 15 and 21, and form with said jaws a toggle construction. Springs 31 and 32 are provided respectively for the jaws 15 and 21, and these springs function to normally hold the lower ends of the jaws 15 and 21 away from the stationary jaws 9 and 12, and up against the toggle plates 25 and 26. These springs 31 and 32 are of the contractile coil spring type, and have their outer ends secured to the lower ends of the jaws 15 and 21, and their inner ends to a cross bar 33, or the like, forming a rigid part of the frame 5. Obviously tensioning means can be provided for these springs without departing from the spirit or scope of my invention.

It is to be also understood at this point that the drawings are of a diagrammatic nature, and merely illustrate the working principles of my invention. In actual practice the machine will be provided with the usual refinements, such as roller bearings and the like for moving parts, and removable wear faces of the desired shape for the facing portions of the jaws 9 and 15, and the jaws 12 and 21.

By referring to the drawings it will be noted that the jaw 21 is arranged closer to its stationary jaw 11 than the jaw 15 to its stationary jaw 9, and consequently the jaws 21 and 11 are adapted to crush rock to a finer degree than the jaws 9 and 15. In actual practice, large rock is placed between the jaws 9 and 15, and as the crushed rock falls from these jaws, the same is screened, and the rock remaining on the screen is placed

between the jaws 21 and 11, and re-crushed to the desired fineness.

Attention is now directed to the novel operation of the movable jaws. During rotation of the cam shaft 13, the cam portion 17 thereof actuates the jaw 15 in a path having a compound movement. That is, the jaw 15 is moved toward and away from the jaw 9, and also longitudinally of the jaw 9. This is not only brought about by the cam portion 17, but also by the toggle plate 25, which allows the lower end of the shaft to have a swinging movement. Synchronous with the operation of the jaw 15, the links 18 are actuated by the cam portion 17 of the shaft 13. Due to the swinging link 23 the ends of the links 18, which support the jaw 21, will not only have a rocking movement up and down, but also a swinging movement back and forth. This movement is enhanced by the swinging toggle plate 26, and thus the jaw 21 is moved toward and away from the jaw 11, and also longitudinally of the jaw 11. The action of the jaws 15 and 21 give an ideal crushing action on the rock, and due to my transmission of power, great force is exerted by the jaws 15 and 21.

From the foregoing description is can be seen that I have provided a double unit crusher of exceptionally simple and durable character, which will expedite the handling and crushing of rock to the desired fineness.

Changes in details may be made without departing from the spirit or scope of my invention, but what I claim as new is:

1. A double unit rock crusher comprising a frame, a power-driven cam shaft rotatably supported by said frame, rock crushing means located at each end of the frame, each of said rock crushing means including a stationary jaw and a movable jaw, swinging links rockably supporting the lower ends of the movable jaws, a sleeve on the upper end of one of said movable jaws rotatably mounted on the cam portion of the shaft, a rock beam supported intermediate its ends, means rockably connecting the rock beam to the upper end of the other movable jaw, and a bearing on the opposite end of the rock beam rotatably receiving the cam portion of the cam shaft.

2. A double unit rock crusher comprising a frame, a drive cam shaft rotatably supported by the frame, rock crushing means mounted at each end of the frame, each of said rock crushing means including a stationary jaw and a movable jaw, a swinging rock link, a rock link rockably mounted intermediate its ends on the swinging rock beam, means rockably connecting the upper end of one movable jaw to one end of the rock beam, means including rock plates supporting the lower ends of the movable jaws, and a bearing sleeve on one movable jaw rotatably receiving the cam portion of the cam shaft, and said rock beam having a bearing portion also receiving the cam portion of said cam shaft.
